(57) **CLAIM**

The ornamental design for a column for a covered walkway or sidewalk shed, as shown and described.

DESCRIPTION

FIG. 1 is perspective view of the column for a covered walkway or sidewalk shed showing our new design in condition of use, with the column being used in conjunction with three other broken line columns installed onto a covered walkway, construction canopy or sidewalk shed, also shown in broken lines;

FIG. 2 is an enlarged view of detail 2 of FIG. 1;

FIG. 3 is an exploded view of the enlarged detail view of FIG. 2 with lightweight broken lines showing the order of assembly;

FIG. 4 is another perspective view thereof;

FIG. 5 is an enlarged view of detail 5 of FIG. 4;

FIG. 6 is an enlarged front elevation view thereof, the rear view being a mirror image thereof;

FIG. 7 is an enlarged right side elevation view thereof, the left side view being a mirror image thereof;

FIG. 8 is an enlarged top side plan view thereof;

FIG. 9 is an enlarged cross-sectional view thereof; taken from line 9-9 of FIG. 6; and,

FIG. 10 is an enlarged bottom plan view thereof.

The evenly dashed broken lines illustrate portions of the column for a covered walkway or sidewalk shed that form no part of the claimed design. The dot-dash broken lines of FIGS. 1-5 depict the boundaries of enlargements and form no part of the claimed design. The lightweight broken lines used in FIG. 3 show the order of assembly of the components in the exploded view and also form no part of the claimed design. The broken away lines on FIGS. 6 and 7 are for the purpose of illustration so that the enlarged, partial views may fit on the page.
